SCOOTER

Lawrence K. Klinker, Huntington Park, Calif.

Application December 8, 1945, Serial No. 633,678

3 Claims. (Cl. 280—29)

1

This invention relates to means facilitating the movement of a person through confined or low-ceilinged places and deals more particularly with a device, which I shall term a scooter board, for the more particular purpose of enabling a person to move through low-ceilinged attics and over the beams or joists which comprise the floor of such attics.

The primary object of this invention is to provide a scooter board of simple, sturdy and effective design, whereby a person can readily move along, across or in a direction at an angle to the beams or joists forming the floor of an attic or other similarly confined and low-ceilinged places.

Another object of the invention is to provide a scooter board of the character referred to which will readily move over beams or joists with little effort on the part of the person propelling the same, and which will safely transport said person through a low-ceilinged attic or similar confined space.

Another object of the invention is to provide a scooter board which incorporates a multiplicity of traction rollers so arranged as to facilitate movement of the board over normal obstructions such as unevenly aligned joists, etc.

My invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes embodiments of the present invention, which are given by way of illustration or example only.

In the drawings, like reference characters designate similar parts in the several views.

Fig. 1 is a side view of a scooter board embodying the present invention and shown in position to travel across joists or similarly spaced members.

Fig. 2 is a bottom plan view thereof.

Fig. 3 is an enlarged fragmentary longitudinal sectional view as taken on the line 3—3 of Fig. 2.

Fig. 4 is an enlarged fragmentary cross-sectional view as taken on the line 4—4 of Fig. 2.

Fig. 5 is a bottom plan view, to a greatly reduced scale, showing an alternate form of construction.

The scooter board which is illustrated in the

5 drawing may be said to comprise, generally, an elongated board 10, a multiplicity of rollers 11 arranged in a plurality of longitudinal lines or rows 12, and means 13 mounting the rollers on the under side of the board.

10 As shown in Fig. 2, the lines of rollers may be three in number, with a line 12a along and adjacent each longitudinal edge 14 of the board 10 and with a shorter line 12b between the lines of rollers 12a and extending from the front edge 15 of the board to an intermediate portion of the length of the board. All of the rollers 11 are arranged transversely of the board and, whereas the rollers of the lines 12a may be generally aligned, those of the line 12b are preferably staggered or offset with respect to the aligned rollers of lines 12a.

20 As shown in Fig. 5, the main body of rollers may comprise a double row or line of rollers 12c in offset relation, as shown, and extending from the front edge 15 of the board 10 to an intermediate point of the rear portion of said board. Another single row 12d of rollers may be provided to extend from the double row 12c to the rear end 25 16 of the board.

20 The arrangement of Fig. 2 affords a more stable support for the board 10 when traveling across joists, whereas the arrangement of Fig. 5, provides for easier guidance of the board along the top surface of a joist. It will be obvious that other arrangements of rows or lines of rollers may be used for obtaining desired stability and directional guidance of the board.

35 The board 10, as shown, is of generally elongated rectangular form and is preferably constructed of wood or other light weight, durable and sturdy material. The general dimensions of the board may be such as to readily span two or more joists and to safely support a person on the board and moving along, across and at an angle to said joists.

40 The rollers 11 are shown as cylindrical members 17, each of a width generally approximating its diameter and integrally formed with opposed trunnions 18. For economy of manufacture and ease of construction, all of the rollers 11 are similar.

45 The means 13 which mounts the rollers 11 in the various rows 12a and 12b of one form of the invention and rows 12c and 12d of the other form, in this instance, is shown as comprising suitably related and associated T-bars 19. Said T-bars are fastened by means of their flanges 20 to the under side of the board 10, nails or screws 21 being used for this purpose. The webs 22 of the

T-bars 19 are formed with bearing holes 23 which, among the related T-bars, are aligned to receive the opposed trunnions 18 of the rollers 10. A typical arrangement is shown in Fig. 4, wherein the rollers extend below the webs 22 so they can readily roll along a surface without interference by their mounting means.

Frequently, the joists or similar members are unevenly set vertically with respect to each other resulting in one or more joists being somewhat elevated relatively to the others. Inasmuch as the present structure is quite low for the purpose of affording access to low-ceilinged places and the rollers 11 are of necessarily small diameter, some difficulty may be encountered in propelling the scooter board across an elevated joist. Accordingly, and in a simple manner, the leading roller or rollers 11a, i. e., those immediately adjacent the front edge 15 of the board, may be mounted to be somewhat elevated with respect to the other rollers 11, as best seen in Figs. 1 and 3. The edge 24 of the web 22 is suitably formed to expose the cylindrical contact surface of said roller 11a. It will be obvious that the arrangement, which also can be provided at the rear end 16 of the board, facilitates smoothly gliding the scooter board over somewhat relatively elevated joists. As a further aid, if desired, the bearing holes 23a for the trunnions of the rollers 11a may be slightly over size, as shown in Fig. 3, to aid the climbing of said rollers over an obstruction as mentioned.

While I have illustrated and described what I now regard as the preferred embodiments of my invention, the constructions are, of course, subject to modifications without departing from the spirit and scope of my invention. I, therefore, do not wish to restrict myself to the particular forms of construction illustrated and described, but desire to avail myself of all modifications that may fall within the scope of the appended claims.

Having thus described my invention, what I claim and desire to secure by Letters Patent is:

1. In a scooter of the type referred to, an elongated board, a pair of spaced inverted U-shaped bars extending from end to end on and secured to the underside of said board, the webs of said bars at the front thereof being upwardly curved, a plurality of trunnioned rollers journaled in said bars and disposed in the same plane, a roller journaled in the upwardly curved portion of each bar and disposed on a higher plane than said plurality of rollers, an inverted U-shaped bar between

said pair of bars and extending from the front of said board to a point intermediate the length thereof, and a plurality of rollers journaled in said intermediate bar.

5 2. In a scooter of the character referred to, an elongated board, an inverted U-shaped bar arranged longitudinally on the underside of said board and along each edge thereof and journaling a plurality of rollers all disposed in the same plane, each of said bars at the forward end thereof being upwardly curved, and provided with holes, the holes in the upwardly curved end being in a relatively higher plane than the remaining holes, trunnioned rollers journaled in said holes, the faces of the rollers in the upwardly curved portions being on a higher plane than the faces of the other rollers, said holes being diametrically greater than the trunnions of said rollers, a bar between said first-named bars extending from substantially an end thereof to a point intermediate the length of said board, and rollers journaled in said bar.

10 3. A scooter board for attics or like confined spaces comprising an elongated support, a plurality of pairs of spaced bars secured to the underside of said support in spaced relation and extending substantially from end to end of the support, a pair of spaced bars between said first-named pairs of bars extending from the front of the support to an intermediate point thereof, a multiplicity of rollers journaled in and between each pair of bars, all of said rollers being disposed in the same plane, and a roller on the underside of the support and adjacent an end thereof, said latter roller being elevated with respect to the other rollers.

LAWRENCE K. KLICKER.
